(57) **CLAIM**

The ornamental design for a fishing line exchange apparatus, as shown and described.

DESCRIPTION

FIG. 1 is a front left perspective view of a fishing line exchange apparatus showing my new design;

FIG. 2 is a front right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front left perspective view thereof with a fishing reel and take-up spindle shown in broken lines; and,

FIG. 10 is a front left perspective view thereof with a fishing reel and supply spindle shown in broken lines.

In the drawings, the broken lines are for illustrative purposes only and form no part of the claimed design.
